Wm A. Morse -

UNITED STATES PATENT OFFICE.

WILLIAM A. MORSE, OF PHILADELPHIA, PENNSYLVANIA.

IMPROVED POLISHING-BOX.

Specification forming part of Letters Patent No. **56,781**, dated July 31, 1866.

To all whom it may concern:

Be it known that I, WILLIAM A. MORSE, of the city and county of Philadelphia, and State of Pennsylvania, have invented a new and useful Polishing-Box; and I do hereby declare that the following is a full, clear, and exact description of the construction and operation of the same, reference being had to the annexed drawing, making a part of this specification.

The nature of my invention consists of a polishing-box adapted to various uses—cleaning knives, forks, spoons, tinware, door-plates, and for general use about a house or shop.

To enable others skilled in the art to make and use my invention, I will proceed to describe its construction and operation.

In the accompanying drawing, A represents a cylinder made of tin, wood, or other suitable material, into the lower end or bottom of which is closely fitted a polishing-pad, B, which may be made of cork, leather, wood, or both combined, or any suitable material for that purpose.

I do not entirely confine myself to this way

of attaching the polishing-pad. It may be attached to any other part of the box most convenient for different kinds of work.

D is a perforated cover or lid made to fit closely around the top of the cylinder A.

To use my invention it is only necessary to provide the cylinder A with suitable polishing-powder, by removing the perforated lid D, and, after replacing it, shake the box with lid downward over the object to be polished, and when a suitable amount of powder is deposited upon the object turn the lid upward and rub the object with the polishing-pad B.

Having thus fully described the construction and operation of my invention, what I claim, as new, and desire to secure by Letters Patent, is—

A polishing-pad, substantially as described, in combination with a box having a perforated lid, for the purpose specified.

WILLIAM A. MORSE.
